UNITED STATES PATENT OFFICE.

FERDINAND G. HENRY, OF PHILADELPHIA, PENNSYLVANIA, ASSIGNOR, BY MESNE ASSIGNMENTS, TO WALDEN KNIFE COMPANY, OF WALDEN, NEW YORK, A CORPORATION OF NEW YORK.

INSPECTING DEVICE.

Application filed February 3, 1921. Serial No. 442,066.

To all whom it may concern:

Be it known that I, FERDINAND G. HENRY, a citizen of the United States, residing at 2908 No. 26th St., North Philadelphia, 5 Pennsylvania, have invented certain new and useful Improvements in Inspecting Devices, of which the following is a clear, full, and exact description.

This invention relates to inspecting devices and more particularly to devices for use in inspecting the edges of blades.

The invention is particularly designed to be applied to a device for use in inspecting the edges of thin removable blades such as 15 are employed in certain classes of safety razors and is shown as embodied in a device particularly adapted to be employed in this operation.

One of the principal objects of the invention is to produce a device by means of which the cutting edges of razor blades may be inspected quickly and easily to determine the condition of the same.

In accordance with this object, the present device is provided with a microscope through which the edges of blades may be inspected and the inventor contemplates as a feature of the invention the provision of means for presenting a blade in predetermined relation to the microscope so that its edge may be inspected through the same. Preferably the blade locating means comprises a blade guideway through which the blades may be passed in succession and in 35 which a blade may be held while its edge is inspected, this guideway being located in predetermined relation to the microscope. In the embodiment of the invention illustrated herein, the guideway is constructed for the passage of blades endwise therethrough, the endwise movement of a blade carrying the blade from the point at which it is inserted in the guideway into position to be inspected through the microscope and 45 from the latter position to the point at which it is discharged from the guideway. Preferably, the blades are carried through the guideway by mechanism arranged to be controlled by the operator.

Another object of the invention is to produce a blade inspecting device by which blades in large quantities may be handled rapidly and efficiently in presenting the blades in position to be inspected and in 55 delivering the blades after they are in-

spected. With this object in view the invention comprises blade handling mechanism involving certain novel and improved features, combinations of parts and constructions hereinafter described and particularly pointed out in the claims. 60

The invention will be clearly understood from the accompanying drawings illustrating a device embodying the invention in its preferred form and the following detailed description of the constructions therein shown. 65

In the drawings,

Fig. 1 is a plan view of a device embodying the invention;

Fig. 2 is a sectional view taken substantially on the line 2—2 of Fig. 1;

Fig. 3 is a view in side elevation of the device looking from the left;

Fig. 4 is a view in vertical section taken substantially on the line 4—4 of Fig. 3; 70

Fig. 5 is a view in vertical section taken substantially on the line 5—5 of Fig. 1;

Fig. 6 is a view in vertical section taken substantially on the line 6—6 of Fig. 1;

Fig. 7 is a view partly in plan and partly 75 in horizontal section illustrating the normal mode of operation of certain of the parts; and

Figs. 8 and 9 are views similar to Fig. 7 illustrating the mode of operation of the 80 parts in discharging a defective blade.

In the preferred form of the invention illustrated in the drawings, a microscope 2 supported on the frame is provided through which the edges of razor blades may be inspected. The blades are presented in predetermined position with relation to the microscope so that the edges thereof may be inspected therethrough by passing the blades through a guideway preferably constructed 90 for the passage of the blades therethrough in a direction substantially parallel with the blade plane. This guideway is indicated at 4 in the drawings and as shown is constructed for the passage of the blades endwise through the same, the guideway having a slightly greater width and thickness than the blades to be inspected. The guideway is formed by registering grooves in two contacting plates 6 and 8 secured to the frame 95 of the machine. 100

The parts are preferably constructed so that a blade may be inspected while it is located in a portion of the guideway intermediate the ends thereof and to this end the 110

plates 6 and 8 and the adjacent part of the frame are cut away forming a recess 10 to expose the edge of a blade when the blade is located in the guideway in line with the 5 recess.

The microscope is located so that it may be directed at the edge of a blade projecting into the recess 10 preferably at an angle of substantially 135° to the body of the blade.

10 This location of the microscope enables the profile of the blade edge and any blunt spots on the edge to be readily seen.

15 The microscope is mounted on an arm 11 adjustably secured by a screw 12 to a support 13 which in turn is adjustably secured by a screw 14 to the frame of the machine. By the adjustment of the arm 11 about the axis of screw 12 and by the adjustment of the support 13 about the screw 14 the microscope 20 may be adjusted angularly in two perpendicular planes, each containing the axis of the microscope to locate the same in the proper angular position. The microscope is longitudinally movable in the arm 25 11 to enable the same to be focused on the edge of a blade and is held in adjusted position by means of a set screw 14^a.

30 The edge of a blade to be inspected is lighted by means of a light 15 mounted within a casing 16 and the rays from the light are preferably concentrated by means of a suitable lens (not shown) located within the casing. Preferably also a reflector is located in the casing behind the light to increase the light directed upon the blade.

35 The light is preferably located so that the rays therefrom are directed at an angle of substantially 135° to the body of the blade under inspection, as shown in Fig. 6. When the microscope and the light are located relatively to the blade as shown and described, the profile of the edge of the blade will show clearly through the microscope and also if any parts of the blade edge are blunted or dulled, this condition may be plainly seen. The location of the microscope and light with relation to the blade and to each other may be varied as found by experiment to give the best results.

40 The casing 16, in which the light is mounted, is secured for adjustment about a horizontal axis to a vertical post or rod 17. The rod 17 is mounted on the outer end of an arm 18 adjustably secured to the frame by means of 45 a stud 19 extending through a longitudinal slot in the arm. This manner of mounting the light enables the same to be adjusted forwardly and rearwardly and angularly in vertical and horizontal planes to locate the same in proper position.

45 The blades are preferably delivered in succession into the guideway 4 by a movement of the blades in a direction substantially normal to the blade plane and to this end the frame is formed with an opening 20

through which the blades are delivered. The blades are carried in succession through the guideway preferably by means of a reciprocating blade actuator. In the present construction the blade actuator indicated at 70 22 consists of a thin blade-like member mounted to slide longitudinally in the guideway 4 and arranged to engage the blades and push the same through the guideway. The blade actuator 22 is reciprocated in 75 the guideway 4 by mechanism arranged to be actuated by the operator so that its movement is under the operator's control. The blade actuator has the following mode of operation. After a blade is carried through 80 the opening 20 into the guideway 4, the blade actuator which is then in its extreme left hand position, is moved to the right by the operator until the blade is carried into a position opposite the recess 10 and 85 is stopped at this point. The blade is then inspected and thereafter the blade actuator is moved still farther to the right to carry the blade into position to be discharged from the guideway. The actuator is then 90 moved back to its extreme left hand position.

95 The mechanism through which the blade actuator is moved in this manner comprises a rod 24 secured to the left hand end of the actuator and a slide bar 26 mounted to slide longitudinally in suitable guides in the frame and carrying an arm 28 surrounding the rod 24 and movable longitudinally thereof. The blade actuator 22 carries a stop 100 block 30 which limits the movement of the actuator to the right and a coiled spring 32 is interposed between said stop block and the arm 28 and normally holds said arm in engagement with a stop collar 34 mounted 105 on the rod 24. The slide bar 26 is reciprocated longitudinally by means of a lever 36 pivoted at 38 on the frame, the forwardly extending arm of which engages between lugs on the slide bar, and the laterally extending arm of which is arranged to be actuated by the operator. The reciprocating movements imparted to the slide bar 26 reciprocate the blade actuator 22 through the action of spring 32 and the engagement 110 of arm 28 with collar 34.

115 The perfect blades are discharged from the guideway 22 also preferably by a movement of the blades in a direction substantially normal to the blade plane and to this 120 end an opening 40 is formed in the frame through which the blades are discharged.

125 The blades in the present machine are delivered successively through the opening 20 into the guideway 4 from a galley 42 and are transferred from said guideway through the opening 40 into a galley 44. These galleries preferably are identical in construction and are removably mounted in the machine so that they may be carried 130

from one to another of a series of machines for performing successive operations upon the blades, the receiving galley of one machine after being filled with blades, being 5 employed as the supply galley of the next machine. The galleys are removably mounted in suitable receiving grooves formed in the frame of the machine as shown clearly in Fig. 2, the grooves being preferably arranged to locate the galleys in positions substantially perpendicular to the guideway 4. The galleys are each provided with a central guideway formed by lateral ribs 46 adapted to receive a series of blades placed face to 10 face as shown in Fig. 7. Each galley carries at one end spring retaining pawls 48 having shoulders formed by inwardly bent portions of the pawls arranged to extend over the ends of the last blade of the pack 15 in the galley to hold the blades in position. To enable the blades to be delivered freely from the supply galley beveled pins 50 are mounted on the frame of the machine in position to engage beveled faces on the retaining pawls and force the pawls back out of blade engaging position when the galley is placed in operating position in the machine as shown in Fig. 1.

The blades are forced along the supply 20 galley in a direction substantially normal to the blade plane to carry the same successively through the opening 20 by means of an arm 52 arranged to engage the rear blade of a pack in the galley as shown in Fig. 1. The arm 52 is secured to a slide block 54 mounted to slide longitudinally on a rod 56 supported at its ends in the frame. To 25 the slide block 54 is secured one end of a cable 58 passing about guide pulleys 60 and 62, to the other end of which cable is secured a weight 64. The weight 64 tends to force the block 54 and the arm 52 toward the forward end of the supply galley and carries the pack of blades along the galley as 30 the blades are passed successively through the guide way 4 by the blade actuator 22.

The retaining pawls 48 of the receiving galley are preferably allowed to assume their normal positions as shown in Fig. 1 and each 35 blade after it is moved into registration with the opening 40 is pushed from the guideway 4 by means of a reciprocating pusher 66 arranged to engage the forward face of the blade and to push the same from the guideway 4 into the receiving galley as shown in Fig. 7. During its movement the ends of the blade engage the beveled ends of the retaining pawls and force the same back and the blade is finally carried past the shoulders 40 on the pawls, the pawls then springing inwardly into blade retaining positions. Reciprocating movements are imparted to the pusher 66 from the slide bar 26. To this end the pusher carries a pin 68 depending 45 therefrom, which engages in a cam groove

70 formed in the slide bar 26. The right hand portion of a cam groove 70 is substantially parallel with the slide bar 26 and the left hand end thereof is formed with an incline as clearly shown in the drawings. As 75 the lever 36 is swung in a direction to carry the slide bar 26 to the right from its extreme left hand position, the pusher 66 is held stationary by the engagement of the pin 68 in the right hand portion of the cam groove 75 80 70 until the blade actuator 22 carries a blade into position to enter the opening 40, the movement of the blade actuator then being stopped by the engagement of the stop block 30 with the frame of the machine. After 85 this occurs the movement of the lever 36 is continued, thereby moving the slide bar 26 independently of the blade actuator against the tension of the spring 32. During this movement of the slide bar the pusher 66 is 90 actuated through the engagement of the pin 68 in the incline in the cam groove 70 to push the blade from the guideway 4 into the supply galley. As the lever 36 is swung in the reverse direction, the slide bar 26 is first 95 moved to the left independently of the blade actuator to retract the pusher 66 until the arm 28 engages the stop 34. The continued movement of the lever then moves the blade actuator to the left with the slide bar. 95

It is not desirable that the blades, the edges of which are found upon inspection to be imperfect, should be delivered into the receiving galley with the perfect blades. To avoid the delivery of an imperfect blade 100 into the receiving galley, the operative movement of the lever 36 following the inspection of such a blade is stopped before the pusher 66 is actuated to push the blade from the guideway into the receiving galley. To 105 this end the laterally extending arm of the lever 36 carries a pivoted stop dog 72, the rear arm of which is arranged to engage a projection 74 on a bracket secured to the frame of the machine to stop the movement 110 of the lever. The stop dog is normally held by a spring 76 in the position shown in Fig. 7, with a projection thereon engaging a stop pin 78 secured in the lever 36. When the stop dog is in this position the lever 36 is 115 free to swing to the end of its operative movement. When, upon the inspection of a blade, the edge thereof is found to be defective, the operator grasps the laterally extending arm of the stop dog 72 and swings 120 the same back into engagement with a stop pin 80 secured in the lever 36, as shown in Fig. 8. When the stop dog is in the position shown in this figure, the operative movement of the lever 36 is stopped by the engagement of the rear arm of the stop dog 125 with the projection 74 with the parts in the position shown in Fig. 8. A blade is thus carried by the movement of the blade actuator imparted thereto by this movement of 130

lever 36 into the right hand end of the guideway 4, but the pusher 66 is still held in retracted position when the movement of the lever is arrested. As the next blade is carried by the blade actuator through the guideway 4 into position to enter the opening 40, the defective blade is pushed beyond the said opening into the extreme end of the guideway by the engagement of the second blade therewith as shown in Fig. 9. This defective blade will be finally ejected from the guideway by the next defective blade as the latter blade is carried into the extreme end of the guideway.

It is to be understood that certain features of the present invention are not limited to machines for inspecting safety razor blades, but that they may be embodied in machines for use in inspecting other kinds of razor blades and also that certain features may be applied to machines for inspecting blades other than razor blades. It is also to be understood that except as defined in the claims, the invention is not limited to the particular construction and arrangement of parts of the illustrated embodiment of the invention, but that the invention may be embodied in other forms within the scope of the claims.

What I claim as new is:

1. A machine for inspecting the edges of blades having in combination a microscope, means for supporting the microscope, and means for relatively presenting to each other the microscope and a blade with its edge exposed and locating said edge in predetermined position with relation to the microscope so that its edge may be inspected therethrough.

2. A machine for inspecting the edges of blades having in combination a microscope, means for supporting the microscope, and means under control of the operator for presenting a blade to the microscope with its edge exposed and locating said edge in predetermined position with relation to the microscope so that its edge may be inspected therethrough.

3. A machine for inspecting blades having in combination a microscope, means for supporting the same in a fixed position, a blade guideway located in predetermined relation to said microscope so that the edge of a blade may be inspected while held at a point in said guideway and means for moving blades in succession through the guideway.

4. A machine for inspecting blades having in combination a microscope, means for supporting the same in a fixed position, a blade guideway located in predetermined relation to said microscope so that the edge of a blade may be inspected while held at a point in said guideway and means under control of the operator for moving blades in succession through the guideway.

5. A machine for inspecting blades having in combination a microscope, means for supporting the same in a fixed position, a blade guideway located in predetermined relation to said microscope so that the edge of a blade may be inspected while held at a point in said guideway, means for moving blades in succession through the guideway, and a supply galley arranged to deliver blades to said guideway.

6. A machine for inspecting blades having in combination a microscope, means for supporting the same in a fixed position, a blade guideway located in predetermined relation to said microscope so that the edge of a blade may be inspected while held at a point in said guideway, means for moving blades in succession through the guideway, and a receiving galley for receiving blades from said guideway.

7. A machine for inspecting blades having in combination a supply galley having a guideway arranged to hold a series of blades placed face to face, a similar receiving galley, a microscope, and means for taking blades in succession from the supply galley presenting the same in predetermined position with relation to said microscope so that the edges thereof may be inspected and delivering the same into the receiving galley.

8. A machine for inspecting blades having in combination a microscope, means for supporting the same in a fixed position, a blade guideway located in predetermined relation to said microscope so that the edge of a blade may be inspected while held at a point in said guideway, a reciprocating blade actuator mounted to slide longitudinally of the guideway and means under control of the operator for imparting reciprocating movements to the blade actuator.

9. A machine for inspecting blades having in combination a microscope, means for supporting the microscope in fixed position, a blade guideway located in predetermined relation to said microscope so that the edges of blades may be inspected while held at a point in said guideway, a supply galley for delivering blades to said guideway, a receiving galley for receiving blades from said guideway, a reciprocating blade actuator mounted to slide longitudinally of the guideway and means under control of the operator for imparting reciprocating movements to the blade actuator.

10. A machine for inspecting blades having in combination a microscope, means for locating a blade with its edge in predetermined relation to the microscope so that said edge may be inspected through the microscope and means for illuminating the edge of a blade located in inspecting position.

11. A machine for inspecting blades having in combination means for locating and holding a blade with its edge in predeter-

mined inspecting position, and a microscope directed obliquely from one side of a blade held in such position against the edge thereof.

- 5 12. A machine for inspecting blades having in combination means for locating and holding a blade with its edge in predetermined inspecting position, a microscope directed obliquely from one side of the blade 10 against the edge thereof and means for directing a light obliquely from the opposite side of a blade held in such position against the edge thereof.
13. A machine for inspecting blades having in combination means for locating and holding a blade with its edge in predetermined inspecting position, and a microscope directed obliquely from one side of a blade held in such position against the edge there- 20 of at substantially an angle of 135° to the body of the blade.

14. A machine for inspecting blades having in combination means for holding a blade in inspecting position, a microscope 25 directed obliquely from one side of the blade against the edge thereof at substantially an angle of 135° to the body of the blade and means for directing a light obliquely from the opposite side of the blade 30 against the edge thereof at substantially an angle of 135° to the body of the blade.

15. A machine for inspecting blades having in combination a microscope, a blade receiving device, means for presenting a blade 35 in predetermined relation to said microscope so that its edge may be inspected therethrough, means for projecting the blades into the receiving device and means under control of the operator for preventing the projection of a defective blade into the receiving device.

16. A machine for inspecting blades having in combination a microscope, a blade receiving device, means for presenting a blade 45 in predetermined relation to said microscope so that its edge may be inspected therethrough, means under control of the operator for projecting the blades into the receiving device and a stop under control of the operator for preventing the projecting 50 of a defective blade into the receiving device by said means.

17. A blade inspecting device having in combination a microscope, a blade guideway located in predetermined relation to the microscope 55 so that the edge of a blade may be inspected while held at a point in said guideway, a blade receiving device, a blade actuator for moving blades through the guideway, a device for projecting blades into the receiving device, means under control of the operator acting first to move the blade 60

actuator to carry a blade through the guideway to discharging position and then to move the projecting device to project the 65 blade from the guideway and means under control of the operator for preventing the operation of the projecting device by said means.

18. A blade inspecting device having in combination a microscope, a blade guideway located in predetermined relation to the microscope so that the edge of a blade may be inspected while held at a point in said guideway, a blade receiving device, a blade actuator for moving blades through the guideway, a device for projecting blades into the receiving device, means under control of the operator acting first to move the blade actuator to carry a blade through the guideway 75 to discharging position and then to move the projecting device to project the blade from the guideway and means under control of the operator for stopping the operation of said last means before the projecting device is operated.

19. A machine for inspecting the edges of blades, having in combination, means for locating a blade in inspecting position, lighting means arranged to illuminate the 90 edge and to show the profile of a blade, and a microscope arranged so that the edge and profile of a blade may be inspected therethrough.

20. A machine for inspecting the edges of blades having, in combination, a microscope and means for taking the blades in succession and presenting the same to the microscope, with the edge of each blade located in the same predetermined position with 100 relation to the microscope so that said edge may be inspected through the microscope.

21. A machine for inspecting the edges of blades having, in combination, a microscope, a blade supply holder, a blade receiving device, and means for taking the blades in succession from the supply holder, presenting the same to the microscope with the edge of each blade located in the same predetermined position with relation to the microscope so that said edge may be inspected through the microscope and thereafter discharging the blade into the receiving device.

22. A machine for inspecting the edges of blades having, in combination, a microscope 115 and means for holding a blade and for relatively locating the blade and microscope with the edge of the blade in a predetermined and definite position with relation to the microscope so that the edge of the blade 120 may be inspected through the microscope.

Signed at New York city, N. Y., this 1st day of February, 1921.

FERDINAND G. HENRY.
